UNITED STATES PATENT OFFICE.

FREDERICK C. OWEN, OF FAYETTEVILLE, NORTH CAROLINA.

TRANSFORMER FOR ELECTRIC-ARC CUTTING AND WELDING APPARATUS.

Application filed November 19, 1925. Serial No. 70,083.

This invention relates to alternating current electric arc cutting and welding apparatus and more particularly to single phase transformers for such apparatus.

5 The invention has for one of its objects to improve and simplify the general construction of transformers of the character stated and to provide transformers that shall be so wound and constructed as to obviate 10 the necessity of the use of fans or other mechanical cooling means and the use of flux diverters, damping devices or manually operated resistances and reactances for regulating the current and potential in the 15 primary and secondary windings.

With the foregoing and other objects in view, the invention consists of the novel construction, combination and arrangement of parts hereinafter fully described and 20 claimed, and illustrated in the accompanying drawing, wherein:

Figure 1 is a diagrammatic view of an alternating current electric arc cutting and welding apparatus embodying a transformer 25 constructed in accordance with my invention,

Figure 2 is a similar view illustrating a slightly modified form of the transformer, and

30 Figures 3, 4 and 5 are similar views illustrating further modified forms of the transformer.

Corresponding and like parts are referred to in the following description, and designated in all the figures of the drawing, by 35 similar reference characters.

Referring in detail to the drawing, and more particularly to Figure 1, 1 designates the core which is of laminated construction 40 and embodies a top leg 2, bottom leg 3, side legs 4, and middle leg 5.

The primary winding of the transformer 45 comprises a section consisting of coils 6, 7 and 8 connected in series and mounted on the legs 2, 3 and 4 at one side of the leg 5, and a section consisting of coils 9, 10 and 11 connected in series and mounted on the legs 2, 3 and 4 at the opposite side of the leg 5. The sections are connected in parallel 50 by wires 12 and 13.

The secondary winding of the transformer

comprises a single coil 14 mounted on the leg 5 and provided with taps 15. One end of this coil is connected by a lead 16 to the work 17 which is to be cut, welded or repaired, and any one of the taps 15 is adapted 55 to be connected by a lead 18 to the cutting, repair or welding electrode 19.

In Figure 2 is shown a slightly modified form of the transformer. This transformer 60 is adapted to permit two cutting, welding or repair operations to be performed at the same time. The core and primary winding of this transformer are similar to the corresponding parts of the transformer shown 65 in Figure 1. It has, however, two secondary windings each embodying a main or voltage regulating coil 20 mounted on the leg 3 and an auxiliary or current regulating coil 21 mounted on the leg 2 and connected in series by a wire 22. The coils 20 are connected to the work 17 by leads 16^a. The coils 21 are each provided with taps 23 any one of which is adapted to be connected to the electrode 19 by a lead 18^a. If desired the 70 secondary windings of this transformer may be connected in parallel or series to adapt the apparatus for performing a single cutting, welding or repair operation.

The core and primary winding of the transformer shown in Figure 3 are similar to the corresponding parts of the transformers shown in Figures 1 and 2. The secondary winding is, however, different and comprises main or voltage regulating coils 24 mounted 80 on the legs 4 and an auxiliary or current regulating coil 25 mounted on the leg 5. These coils may be connected in parallel or in series, as shown in the drawing, and the coil 25 is provided with taps 26 any one 85 of which may be connected to the electrode 19 by a lead 18^b, and one of the coils 24 is connected to the work 17 by a lead 16^b.

A further modified form of the transformer is shown in Figure 4. This transformer 90 embodies a core and primary winding similar to the corresponding parts of the transformers shown in Figures 1, 2 and 3. The secondary winding of this transformer 95 differs from the secondary windings of said other transformers, and comprises a section 100 consisting of main or voltage regulating coils

27 and 28 mounted on the legs 2 and 3 at one side of the leg 5, a section consisting of main or voltage regulating coils 29 and 30 mounted on the legs 2 and 3 at the opposite side 5 of the leg 5, and a section consisting of an auxiliary or current regulating coil 31 mounted on the leg 5. The respective sections of the main or voltage regulating coils 27—30 are connected in parallel, and these 10 sections are connected in series with the auxiliary or current regulating coil 31. The coils are connected by a lead 16° to the work 17. The coil 31 is provided with taps 32 any one of which is adapted to be connected to 15 the electrode 19 by a lead 18°.

In Figure 5 there is shown a still further modified form of the transformer. The core and primary winding of this transformer are similar to the corresponding parts of 20 the other transformers, but the secondary winding is different. This secondary winding comprises a section consisting of main or voltage regulating coils 33 and 34 mounted on the legs 2 and 3 at one side of the leg 5, a section consisting of main or voltage regulating coils 36 and 37 mounted on the legs 2 and 3 at the opposite side of the leg 5, and a section consisting of an auxiliary or current regulating coil 38 mounted on the 25 leg 5. These coils are connected in series, and the coil 38 is provided with taps 39 any one of which is adapted to be connected to the electrode 19 by a lead 18°. This coil is connected to the work 17 by a lead 18°.

In each transformer, the core provides a plurality of completely closed magnetic paths, the primary winding has a section distributed about the greater portion of each of said paths, and the secondary winding is 30 distributed about both of said paths. When current flows through the primary winding, a constant main voltage and a variable secondary voltage will be induced in the secondary winding. The reaction between these 35 voltages is such that there is induced, in the secondary circuit including the work and electrode, a light current at light load and a heavy current at heavy load, with the result that a stable arc of high power factor may 40 be readily maintained during overhead, vertical and horizontal cutting, welding or repairing of steel, wrought iron, cast iron, malleable iron, aluminum, brass, bronze, copper and alloy metals. Furthermore, the arc 45 is free from sputtering and spitting, and it has been found that a skilled operator can maintain an arc within one and one-half per cent plus or minus of the rated capacity of the tap with which the electrode is connected.

What is claimed is:—

1. A transformer comprising a core providing a plurality of closed magnetic paths, a primary winding embodying sections distributed around the greater portion of each 55

of said paths, and a secondary winding distributed around a plurality of said paths.

2. A transformer comprising a core providing a plurality of closed magnetic paths, a primary winding embodying sections each distributed around the greater portion of each of said paths, and a secondary winding embodying coils distributed around different portions of said paths.

3. A transformer comprising a core having top, bottom, side and middle legs, a primary winding comprising similar sections distributed around said top, bottom and side legs at opposite sides of said middle leg, and a secondary winding distributed around the middle leg.

4. A transformer comprising a core having top, bottom, side and middle legs, a primary winding comprising similar sections distributed around the top, bottom and side 35 legs at opposite sides of the middle leg, and a secondary winding distributed around the top and bottom legs at opposite sides of the middle leg.

5. A transformer comprising a core having top, bottom, side and middle legs, a primary winding comprising similar sections distributed around the top, bottom and side legs at opposite sides of the middle leg, and a secondary winding distributed around the 45 top, bottom and middle legs.

6. A transformer comprising a core having top, bottom, side and middle legs, a primary winding comprising similar sections distributed around the top, bottom and side 50 legs at opposite sides of the middle leg, and a secondary winding embodying coils distributed around the top and bottom legs and connected in parallel, and a coil distributed around the middle leg and connected in series 55 with said other coils.

7. A transformer comprising a core having top, bottom, side and middle legs, a primary winding comprising similar sections distributed around the top, bottom and side 60 legs at opposite sides of the middle leg, and a secondary winding distributed around the middle and two of the other legs of the core.

8. A transformer comprising a core having top, bottom, side and middle legs, a primary winding distributed about the top, bottom and side legs only of the core, and a secondary winding having coils on the top and bottom legs of the core.

9. A transformer comprising a core having top, bottom, side and middle legs, a primary winding distributed about the top, bottom and side legs only of the core, and a secondary winding on the core and having a portion thereof closely associated with the primary winding and a portion remote from the primary winding.

10. A transformer comprising a core providing a plurality of closed magnetic paths, a primary winding embodying sections dis- 130

tributed about a portion of each of said paths and connected in parallel, and a secondary winding distributed around a plurality of said paths.

- 5 11. A transformer comprising a core providing a plurality of closed magnetic paths, a primary winding embodying sections dis-

tributed around a portion of each of said paths, each section comprising coils connected in series and the sections being connected in parallel, and a secondary winding distributed around a plurality of said paths. 10

In testimony whereof I affix my signature.

FREDERICK C. OWEN.
